(57) **CLAIM**

I claim the ornamental design for a interchangeable bra, as shown and described.

DESCRIPTION

FIG. 1 is a Front Perspective View of an interchangeable bra showing my new design;

FIG. 2 is a Front View thereof;

FIG. 3 is a Rear View thereof;

FIG. 4 is a Left Side View thereof; and,

FIG. 5 is a Right SideView thereof.

The broken lines shown are included for the purpose of illustrating portions of the interchangeable bra that form no part of the claim.

1 Claim, 5 Drawing Sheets

FIG. 1

FIG. 2

FIG. 3

FIG. 4

FIG. 5
